his Attorney.

UNITED STATES PATENT OFFICE.

HARVEY C. SAWYER, OF ST. PAUL, MINNESOTA.

RAILWAY-TRACK.

1,399,802.

Specification of Letters Patent. Patented Dec. 13, 1921.

Application filed October 13, 1920. Serial No. 416,609.

To all whom it may concern:

Be it known that I, HARVEY C. SAWYER, a citizen of the United States, residing at St. Paul, in the county of Ramsey and State of Minnesota, have invented new and useful Improvements in Railway-Tracks, of which the following is a specification.

My invention relates to improvements in railway tracks.

10 Its object is to provide a track that is inexpensive to construct, easy to lay, and durable in use.

15 A further object of my invention is to provide a joint, between rails of a track, which will eliminate noise and jar to the rolling stock.

Another object of my invention is to secure rigidity and safety in rail joints.

20 A still further object of my invention is to provide a track, in which the rails are joined at their ends, in a manner to effect a material saving of metal and one which precludes the necessity for periodically cutting off the ends of the rails.

25 As is well known, railway rails, in common use, are so joined at their ends that the impact of the rolling stock, in passing over the joints, causes a clicking noise and also in time wears down the ends of each rail in a manner to make it necessary to periodically cut off the ends of each rail. This repair work requires an expensive cutting machine and much labor and greatly increases the cost of operation.

30 Further, the rails, as usually joined, are held together at their ends by fish plates or angle bars and bolted together through the web of the rail. In my improved rail I do away with these fish plates, angle bars and bolts, and also by a novel form of end, on each rail, the joints are made practically silent. Other advantages and objects of my improved rail will hereinafter appear and be more fully pointed out in the claim.

45 Referring to the accompanying drawings Figure 1 is a plan view of my improved rail showing a joint and both ends of one rail; Fig. 2 is an elevation of the same; Fig. 3 is a section taken on the line 3—3 of Fig. 1 and 50 Fig. 4 is a detail perspective view of one end of one of the rails.

My rail includes the usual type of ball or tread 10 supported by a web 11 on a flange 12. The rails are fastened to the ties by means of the usual type of spikes 13 which pass through perforations 14 in the flanges 12. The web 11 is thickened at 11^a, near the end of each rail section, to give the necessary strength and to securely interlock the abutting surfaces of the rails their ends are cut 60 to form three distinct, plain surfaces 15, 16 and 17 (Fig. 4). The surfaces 15 and 17 form oblique, vertical and horizontal angles with the surface 12^a of the flanges 12, while the surface 16 (the longest of the three end 65 surfaces) is vertical but extends at an angle with the center line of the surface 12^a. Thus the end of each rail is under-cut at the surface 15, so that it tends to support the surface 17 of the abutting end. 70

To further insure a rigid joint I provide a stiffening plate 18 which extends longitudinally a short distance beyond the surfaces 15 and 17 at each joint. Laterally the plate 18 projects beyond the flanges 12 and is 75 formed with upwardly extending flanges 19 which, when the rails are spiked to the ties, still further increase lateral rigidity.

In laying a track of my improved rails the several sections are placed end to end on any 80 suitable ties and are secured to the latter by spikes through the perforations 14 in the flanges 12. The ends of each rail section interlock with the adjacent rails as shown in Figs. 1 and 2. Two ties 20 and 21 are placed 85 beneath the ends of the stiffening plate 18 and the spikes 13 are driven into these ties through the perforations 14 in the flanges 12 and similar perforations in the plate 18. All of the ends being identical, one rail may 90 be easily substituted for another.

In use as the rolling stock passes from one rail section to the next the weight first arrives over the end surface 15 and tends to depress this end of the rail. This tendency 95 is opposed not only by the rigid plate 18 which distributes the weight between abutting rail ends but also by the under-cut character of the surface 15 which is supported by the surface 17 on the adjacent rail. Thus, if 100 an end should be depressed the adjacent rail end will also be depressed an equal amount.

The coöperation of the parts obviates the usual clicking and wearing down at the joints.

Having described my invention what I claim as new and desire to protect by Letters Patent is:

In a railway track a plurality of rail sections having ends formed by two inclined plain surfaces and a vertical plain surface

intersecting said inclined surfaces obliquely, 10 a plate adapted to support the junction of rail sections and means for securing said plate against longitudinal and transverse movement.

In testimony whereof I have hereunto sub- 15 scribed my name to this specification.

HARVEY C. SAWYER.
